UNITED STATES PATENT OFFICE.

ALEXANDER H. DAVISON, OF ATHENS, GEORGIA.

DESIGN FOR A FAN-RACK.

SPECIFICATION forming part of Design No. 24,680, dated September 17, 1895.

Application filed August 14, 1895. Serial No. 559,287. Term of patent 14 years.

To all whom it may concern:

• Be it known that I, ALEXANDER H. DAVISON, of Athens, in the county of Clarke and State of Georgia, have invented a new and original Design for a Fan-Rack, of which the following is a full, clear, and exact description.

Reference is to be had to the accompanying drawing, which is a perspective view of a fan-rack having the essential features of my design. These features consist in the figures A, having a star-like appearance and having, further, a configuration B at their centers, imparting to them a concentric circular appearance. The arms of the star-like figures have a serrated or toothed appearance.

The minor features of the design lie in the vertical assemblage of the star-like figures A, apparently on a column D, having an apparently circular base-figure E and scroll-like figures F, seemingly braces for the column. 20

I claim—

The design for a fan-rack, substantially as herein shown and described.

ALEXANDER H. DAVISON.
